OVERHEAD VALVE TAPPET CLEARANCE
ADJUSTING WRENCH

George S. Morris, North Hollywood, Calif.

Application June 21, 1945, Serial No. 600,751

2 Claims. (Cl. 81—56)

1

This invention relates to an overhead valve tappet clearance adjusting wrench.

One of the main objects of the invention is to provide a device that will reduce the number of hand operations required in adjusting overhead valve tappets.

The device will permit the unlocking of the valve adjusting screw locknut, the raising or lowering of the valve adjusting screw to obtain the desired clearance and the relocking of the valve adjusting screw locknut with one hand of the operator. This will permit the other or free hand to use an appropriate feeler gauge, thus rendering a faster and more accurate valve clearance adjustment.

Another object of the invention is to provide a device that is fully demountable, therefore permitting the various parts thereof to be replaced, eliminating the necessity of purchasing an entire new wrench when the parts become worn.

A further object of the invention is to provide a device that will accommodate various sizes of valve adjusting screw locknuts that are employed on overhead valve engines for automobiles or airplanes.

A still further object of the invention is to provide a device that will obtain the desired clearance with a minimum amount of effort on the part of the operator.

Other objects and advantages of the invention will become apparent as the description progresses.

In the accompanying drawing forming a part of this specification, and in which like reference characters are employed to designate corresponding parts throughout the same:

Fig. 1 is a top plan view of an embodiment of the invention, and

Fig. 2 is a side view thereof partly in section.

Referring more particularly to the drawing the numeral 5 designates the wrench head of the tool which is square in shape and comprises an upper wrench head plate 7, a lower wrench head plate 9, front wrench head plate 11 and rear wrench head plate 13, suitably secured together to form a square by upper and lower wrench head plate retainer screws 15, of which there are eight in number.

The lower wrench head plate 9 is provided with a socket wrench receiving opening 17 which is adapted to receive the reduced portion 19 of a socket wrench 21.

The opening 17 is provided with the usual socket retaining ball 23 which is operated by

2

tension from the socket retaining ball tension spring 25.

The upper wrench head plate 7 is provided with screw-driver blade receiving opening 27 which is adapted to receive the upper end 29 of the screw-driver blade 31.

The screw-driver blade 31 is in vertical relation with the socket wrench 21 and the screw-driver blade receiving opening 27 is in alignment with an opening 33 in the reduced portion 19 of the socket wrench 21.

The screw-driver blade 31 enters the socket 35 of the socket wrench 21 a sufficient distance to be inserted into the usual kerf of the valve adjusting screw, not shown.

Secured to the screw-driver blade 31 is a bevel gear driven member 37 which is secured thereto in any well-known manner in this instance by spot welds 39.

20 The upper end 29 of the screw-driver blade 31 is provided with a reduced squared portion 41, which is adapted to be received in the square opening 43 of a screw-driver blade manually operated handle 45.

25 The reduced squared portion 41 is provided with an internally threaded bore 47 to receive a complementary threaded screw-driver blade manually operated handle retainer screw 49 and washer 50, which retains the screw-driver blade

30 manually operated handle 45 on the reduced squared portion 41.

The rear wrench head plate 13 is provided with a circular opening 47.

In alignment with and at right angles to and 35 formed integral with the rear wrench head plate 13 is a tubular handle bearing 49.

The reduced circular portion 51 of the cylindrical wrench handle 53 is slidably received in the tubular handle bearing 49 and is retained therein 40 by means of a handle retainer screw 55 which is received in the complementary threaded opening 57 which is adjacent the end of the tubular handle bearing 49, and enters a circular retainer screw receiving groove 59 in the reduced circular portion 51 of the cylindrical wrench handle 53.

The reduced circular portion 51 is provided with a circular shank 61 on which is rotatably mounted a bevel gear driving member 63. The circular shank 61 is provided with an internally threaded bore 65 which is adapted to receive a complementary threaded bevel gear driving member retainer screw 67 and washer 68 which retains bevel gear driving member 63 on the circular shank 61.

55 Interposed between the shoulder 69 formed at

the junction 71 of the reduced circular portion 51 and the knurled hand grip 73 of the cylindrical wrench handle 53 and the end 75 of the tubular handle bearing 49 is a bevel gear disengaging spring 77.

This spring is designed to normally disengage the bevel gear driven member 37 and the bevel gear driving member 63.

In the operation of the device the socket wrench 21 is positioned over the valve adjusting screw locknut. The screw-driver blade 31 is manually positioned by the handle 45 so that the tip of the screw-driver blade 31 is received into the kerf of the valve adjusting screw. With the handle 53 in normal position, i. e., with the gears 37 and 63 disengaged the handle is rotated in a horizontal plane on the axis formed by the screw-driver blade 31 in a counterclockwise direction to loosen the valve adjusting screw locknut.

With one hand the operator pushes the handle 53 towards the wrench head 5, engaging bevel gears 37 and 63 then, by rolling or rotating the handle 53, the hand of the operator will transmit such action through the gears 37 and 63 to the screw-driver blade 31 to the valve adjusting screw which will, depending on the direction of the rolling or rotating, raise or lower the valve adjusting screw. During this operation, the operator with his free hand can insert an appropriate feeler gauge between the valve adjusting screw and tappet to obtain the desired clearance. If it is desired to raise or lower the valve adjusting screw through the medium of the screw-driver alone such may be accomplished by manually rotating the screw-driver by means of the handle 45 secured to the upper end of the screw-driver. In this instance the handle 53 will not be pushed inwardly to cause the gears 37 and 63 to become engaged.

After this has been obtained the handle 63 is allowed to slip in the operator's hand, disengaging the bevel gears 37 and 63 by action of the bevel gear disengaging spring 77. Then by firmly grasping the handle 45 so that the position of the valve adjusting screw is maintained, the handle 53 is rolled or rotated in the opposite or clockwise direction to tighten the valve adjusting screw locknut.

The operation being repeated on each valve of the engine desired to be adjusted.

Having thus described only a typical embodiment of the invention, it is to be understood that the invention is not to be limited or restricted to the particular details hereinabove set forth and that various changes as to the shape, size and

arrangement of parts that may appear to those skilled in the art may be resorted to without departing from the spirit of the invention or the scope of the subjoined claims.

Having thus described the invention what is claimed as new and desired to be secured by Letters Patent is:

1. A device of the character described, comprising a substantially square shaped wrench head formed of upper and lower and front and rear plates, means for removably joining said plates to form the head, a socket wrench mounted in the lower plate of said head, a screw-driver perpendicular to said head having a handle attached to one end thereof, the other end thereof terminating in the socket of said socket wrench, a tubular handle bearing formed integral with said rear plate at right angles thereto, and means for rotating said screw driver, said last mentioned means comprising a handle slidably and rotatably mounted in the handle bearing and cooperating disengageable means on the inner end of the handle and on the screw-driver to rotate said screw-driver upon rotation of said handle.

2. The invention as in claim 1 wherein a circular groove is provided in said last mentioned handle, and means for retaining said last mentioned handle is mounted in said bearing for co-action with said groove, and the cooperating means comprises a bevelled gear positioned on the inner end of said last mentioned handle within said head and a bevelled gear located on said screw driver adapted to mesh with the gear on said last mentioned handle upon forward sliding movement of said last mentioned handle, and means is located between and contacts with said bearing and said last mentioned handle to force said last mentioned handle rearwardly to disengage said gears.
